Hanson and Hanson

UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC FITTING.

1,392,091.

Specification of Letters Patent. Patented Sept. 27, 1921.

Application filed December 4, 1918. Serial No. 265,254.

To all whom it may concern:

Be it known that I, GEORGE B. THOMAS, a citizen of the United States of America, residing at Bridgeport, in the county of Fairfield and State of Connecticut, have invented certain new and useful Improvements in Electric Fittings, of which the following is a specification.

My invention relates to electric fittings and particularly to a fitting of the type comprising a combined electric lamp socket and attachment plug receptacle. The special object of my invention is to provide a receptacle unit adapted to be combined with the elements of a standard socket to supplement the latter and thus afford a combined fitting adapted not only to receive a lamp but also to provide an independent receptacle to receive the jacks of an attachment plug.

In the accompanying drawings,

Figure 1 is a side elevation, partially in section, showing a combination fitting in which my invention is embodied in one form.

Fig. 2 is a dropped perspective of the fitting elements detached.

Fig. 3 is a cross section through the plug receptacle element on the line 3—3 of Fig. 1.

Fig. 4 is a section on the line 4—4 Fig. 3.

In the embodiment of my invention here illustrated by way of example, I have shown a standard porcelain wall socket comprising a base 10 and body 11 which when united form a lamp receptacle. The base is pierced at 12 and 13 to receive securing screws by means of which the fitting may be mounted on any suitable support. Bosses 14 and 15 project from opposite sides of the base and support straps 16 and 17 carrying binding screws 18 and 19 for the leading-in wires. These straps are secured to the base by bolts 20 and 21 passing through the base. The inner end of strap 17 is tapped at 22 to receive a bolt 23 from the body 11. A tapped ferrule 24 is secured to the base 10 and receives the threaded end of the bolt 25 carried by the body 11. The inner end of strap 16 is offset to afford a spring terminal 26 arranged in position to coöperate in assembled condition with the spring terminal 27 carried by the socket body 11. An annular flange 28 on the base centers the adjacent end

of the body 11 with relation to the base, while a lug 29 projecting inward from the flange engages a notch 30 in the lower face of the body 11 and insures the registry of the screw bolt 25 with the tap 22 in the strap 17 and the engagement of the terminals 26 and 27. The socket body 11 carries, in the form shown, a switch mechanism operated by a thumb piece 31 to accommodate which a recess 32 is formed in the periphery of the base 10. The connections to the shell and center contacts (not shown) of the body 11 are made, on the one hand through the screw bolt 23 to the shell, and on the other hand through the switch mechanism to the center contact, in well known manner. The screw bolt 25 which engages the ferrule 24 serves merely as a holding screw.

In the present construction the lamp socket is supplemented by an attachment plug receptacle inserted between the base 10 and the socket body 11 and it is to the receptacle element that the invention particularly relates. In the form here shown, this receptacle comprises an insulating button 33 having a marginal rabbet 34 to fit within the flange 28 of the base 10 and a notch 35 (Fig. 4) to fit the boss 29 to properly position the parts with relation to the coöperating elements on the base; while an annular flange 36 and boss 37 on the opposite face of the button center and properly locate the coöperating elements on the juxtaposed face of the socket body 11. The button is recessed on the face thereof adjacent to the socket body, to afford a pair of insulating chambers 38 and 39 within which are located straps 40 and 41 which serve as conducting connection between the straps 16 and 17 on the base 10 and the coöperating elements on the body 11. As here shown, the strap 40 is offset at its lower end and held in position by a tubular rivet 42 through which passes a bolt 43 taking into the tap 22 in the strap 17 and thus mechanically and electrically connecting these elements. The upper end of the strap 40 is offset to form a terminal 44 adapted to be engaged by the spring terminal 27 of the socket body in the assembled position of the parts. In the chamber 39 the strap 41 is secured in like manner at its offset lower end by the tubular rivet 45 which also holds against the lower

face of the button a brush 46 adapted to make contact with the terminal 26 on the base. A bolt 47 passing through the rivet 45 engages the tapped ferrule 24 in the base 10 and thus not only aids in holding the button in position but in forcing the terminals 46 and 26 into good electrical connection. At its upper end, the strap 41 is offset and tapped at 48 to receive the screw bolt 23 on the socket body 11, which thereby 15 electrically connects the strap 16 on the base with the screw shell contact (not shown) on the socket body. A strap 49, let into the upper face of the button and held by a bolt 50, is tapped at 51 to receive the screw bolt 25 of the socket body 11 which assists in mechanically securing the latter in assembled position.

The button 33 is also provided with a 20 marginal nose 52 through which open independent passages 53 and 54 leading respectively to the chambers 39 and 38. Into these passages project receptacle terminals 55 and 56, here shown in the form of 25 brushes respectively connected at their inner ends to the straps 40 and 41. The passages 53 and 54 are properly spaced to receive the jacks of a coöperating attachment plug, which enter these passages and make 30 contact with the brushes 55 and 56 in a manner readily understood by those skilled in the art. In the present construction the nose 52 of the button 33 is so located that it registers with the recess 32 in the base, 35 which thus affords clearance for the usual head of the cap carrying the plug jacks.

While I have shown my invention in a fitting comprising a socket of the switch type in which a thumb piece 31 is utilized to operate the switch, a socket body of any other 40 type may be substituted therefor provided it has the necessary coöperating conductors. Various modifications in details of construction of the button 33 to adapt it to socket 45 bases for lamp bodies of different type, will readily occur to those skilled in the art without departing from what I claim in my invention.

I claim:

50 1. An electric fitting having independent insulating blocks, wire terminals carried by one of said blocks, lamp terminals carried by the other of said blocks, and means for mechanically securing said blocks together and 55 for establishing electric connection between the respective wire and lamp terminals thereon to form a complete, selfcontained lamp socket, in combination with an insulating button adapted to be interposed between said 60 base and socket body and having conductors coöperating with the conductors thereof together with receptacle contacts electrically connected to said conductors and marginal passage means opening to said receptacle 65 contacts and adapted to form guide means

for the coöperating contacts of an attachment plug.

2. An electric fitting having independent insulating blocks, wire terminals carried by one of said blocks, lamp terminals carried by the other of said blocks, and means for mechanically securing said blocks together and for establishing electric connection between the respective wire and lamp terminals thereon to form a complete, selfcontained lamp 75 socket, an interposed insulating button, conductors on said button establishing electrical connection between coöperating conductors on said base and lamp body together with receptacle terminals carried by said body 80 and accessible through the margin of the plug to the contacts of a coöperating plug.

3. A plug receptacle comprising a button having on its opposite faces, terminals 85 adapted to connect with coöperating conductors on associated elements of an independent self contained electrical fitting together with receptacle terminals electrically connected in the fitting circuit and accessible through the margin of the button to the contacts of a coöperating plug.

4. In an attachment plug receptacle an insulating button recessed from one face to afford independent chambers, conductors mounted on said button and passing through 95 said chambers to the opposite faces of the button together with receptacle terminals projecting from said conductors and accessible through the margin of the button for the purpose described.

5. In an attachment plug receptacle an insulating button recessed from one face to afford independent chambers, conductors mounted on said button and passing through 105 said chambers to the opposite faces of the button together with receptacle terminals projecting from said conductors and accessible through independent passages in the margin of the button for the purpose described.

6. In an attachment plug receptacle, an insulating button marginally recessed to house plug receptacle terminals, terminal contacts arranged in said housing, conductors associated with said terminal contacts 115 and mounted on said button, means establishing electrical connection between said conductors and conductors on an associated wire terminal block facing one side of said button, and independent means to establish 120 electrical connection between said terminals and conductors on an associated lamp receptacle block facing the opposite side of said button.

7. An electrical fitting comprising an insulating block, combined wire terminal and connecting straps mounted thereon, an associated insulating block, lamp terminals mounted thereon, and means for mechanically connecting said blocks and establishing 125 130

electrical connection between said lamp terminals and the connecting straps on the wire terminal block in combination with an insulating button adapted to be interposed between said blocks, plug receptacle terminals mounted on said button, means for electrically connecting the same with the wire terminal straps on one of said blocks, and means for establishing connection therethrough to the lamp terminals on the other of said blocks.

In testimony whereof I have signed my name to this specification.

GEORGE B. THOMAS.
